UNITED STATES PATENT OFFICE.

IVAN FOX, OF LANSDOWNE, PENNSYLVANIA.

DESIGN FOR A NOSE-PIECE FOR SPECTACLES OR EYEGLASSES.

SPECIFICATION forming part of Design No. 35,552, dated January 7, 1902.

Application filed October 24, 1901. Serial No. 79,881. Term of patent 14 years.

To all whom it may concern:

Be it known that I, IVAN FOX, a citizen of the United States, residing at Lansdowne, in the county of Delaware and State of Pennsylvania, have invented and produced a new and useful Design for Nose-Pieces for Spectacles or Eyeglasses, of which the following is a specification, reference being had to the accompanying drawings, forming part thereof.

Figure 1 is a view in face elevation of a nose piece showing my new design.

Figure 2 is a view of the same in edge elevation.

As shown in the drawings, the leading feature of the design of my invention consists of the configuration and arrangement of the parts as follows:—

The plate strip *a* connects to the edge of the plate strip *c*, and said plate strip *a*, which is

in approximately the same plane as the strip *c*, extends away from the body of the plate strip *c*. The plate strip *c* is as to its free upper end, equipped with an oval enlargement or plate *e*, connected with it through a neck *d* of reduced breadth as compared with the body of the strip *c*, which enlargement or plate has a large central elongated aperture *f*.

I claim—

The design for a nose-piece for spectacles and eyeglasses, as herein shown and described.

In testimony that I claim the foregoing as my invention, I have hereunto signed my name this 7th day of October, A. D. 1901.

IVAN FOX.

In presence of—

S. SALOME BROOKE,
THOS. K. LANCASTER.
